UNITED STATES PATENT OFFICE

2,576,165

ELECTRIC SOCKET MEMBER HAVING PLUG-IN OPENINGS FOR THE PRONGS OF A PLURALITY OF PLUGS

John R. Wood, Burbank, Calif., assignor of one-third to John R. Wood, one-third to Thomas J. Wood, Sr., and one-third to Thomas J. Wood, Jr., joint trustees

Application February 24, 1948, Serial No. 10,277

3 Claims. (Cl. 173—334)

1

This invention relates to a portable electric plug or current distributing device having a plurality of outlet sockets, whereby electric current may be readily distributed from a main supply source to a plurality of electrically operated devices (for instance, light bulbs) for operation independently one from the other. The invention is particularly applicable in connection with a display, such as Christmas trees, especially with trimmings thereon, where parts of the display are to be illuminated without undue exposure to view of the equipment (wires and connections) employed for supplying electric current to the light bulbs, at the same time providing a distributing device which lends itself for ready incorporation or mounting in the display. Thus, the distributing device may be located for ready accessibility while providing desirable locations for the light bulbs of an illumination system to produce maximum lighting and decorative effects.

One object of the invention is to provide an improved portable device of relatively simple construction for distributing electric current supplied from a main source to a plurality of connectors.

Another object of the invention is to provide an improved portable device for distributing electric current capable of ready and economical fabrication and assembly and having a large number of outlets.

Another object of the invention is to provide an improved current distributing device enclosing electric conductors and having provision therein for securing the conductors to the device to prevent displacement of either or both conductors.

Another object of the invention is to provide an improved current distributing device adapted to support a plurality of plugs and consisting of a pair of elongated sections and a pair of longitudinally extending electric conductors therebetween, the inner walls of said sections being constructed to secure the conductors against endwise movement.

Another object of the invention is to provide an improved current distributing device consisting of a pair of elongated members formed of non-conducting material the opposed faces of which are formed with longitudinally extending grooves for conductors and having plug-in sockets formed in the opposite outer faces of the members to provide for a large number of outlets.

A further object of the invention is to provide improved electrical connections between a cur-

2

rent supply source and the leads for an electrically operated device wherein provision is made to eliminate danger of fire due to short circuiting or arcing.

5 Other objects of the invention will be apparent to those skilled in the art to which my invention relates from the following description taken in connection with the accompanying drawings, wherein:

10 Fig. 1 is a diagrammatic view showing a front elevation of a Christmas tree in outline with an illumination system applied thereto embodying the principle of the invention.

Fig. 2 is a side elevation of a multiple plug socket with plugs and connectors positioned at each side thereof.

15 Fig. 3 is an elevation showing the left-hand side of the structure illustrated in Fig. 2, the conductors being omitted.

Fig. 4 is a transverse sectional view of the structure shown in Fig. 2 as shown along the line 4—4 looking in the direction of the arrows.

Fig. 5 is a central horizontal sectional view taken along the line 5—5 shown in Fig. 4, looking in the direction of the arrows.

20 Fig. 6 is an enlarged detail view, partly in section, showing the manner in which a prong is connected with a conductor.

Fig. 7 is an end view taken along the line 7—7 shown in Fig. 4, looking in the direction of the arrows.

Fig. 8 is a top plan view, partly in section, illustrating a modified construction of branch connector unit.

25 Fig. 9 is a sectional view of the structure shown in Fig. 8 as seen along the line 9—9, looking in the direction of the arrows.

Fig. 10 is a view similar to Fig. 9, but showing a modification.

30 Fig. 11 is a fragmentary view similar to Fig. 4, but showing a different form of construction.

Fig. 12 is an elevation on the line 12—12 of Fig. 11.

Fig. 13 is a fragmentary section on the line 45 13—13 of Fig. 11, enlarged.

The invention herein disclosed is shown for illustrative purposes as applied to a Christmas tree, whereby the latter may be illuminated to form a display. In such a display one or more distributing devices or multiple plug sockets (three being shown in Fig. 1), each indicated as an entirety at 1, may be employed. 1a indicates a cable embodying a pair of conductors 2, 3, and having a plug terminal adapted to be connected to a standard type of transformer 5 preferably supplying

low voltage such as, for example, 12 volts. The transformer is connected to a source of current by a cable terminating in a plug 7.

When it is desired to use 110 volts for the illumination system, the plug 4 is directly connected to the source of current in place of the plug 7, as will be well understood. The main line cable 1a is shown as provided with a plurality of multiple plug sockets 1, the end socket 1 being provided with a suspension hook 14, whereby it may be engaged over a branch near the upper portion of the Christmas tree.

Inasmuch as each of the branch lines is engaged or electrically connected with a source of current at one of the multiple plug socket devices 1, it is obvious that the first step in decorating a Christmas tree is to place the hook 14 adjacent the upper part of the tree and thus dispose the multiple plug sockets 1 at suitably spaced intervals along the trunk of the tree. This operation is conducted independently of the positioning of any branch lines of conductors and thus no interference with any ornaments already on the tree will take place. The placing of the lights about the tree, accordingly, will be an independent operation for each bulb and its associated conductor, and the artistic grouping or assembling of the lights in suitable relation to other ornaments can be accomplished in a manner to produce the maximum decorative effect over the entire area. Thus, with the multiple plug conductors in place, the individual branch lines, for instance the line 15, can be plugged into the adjacent multiple socket 1 by means of the plug 16 and the bulb 17 in the socket 18 will thus be in direct connection with the circuit since the conductor 15 has two wires and thus completes a circuit to each bulb individually. As shown, the substitution of a number of bulbs connected in a series with a single plug such as the plug 16 may be substituted for the line 15 and its associated parts so as to provide a cluster illumination of low voltage bulbs in the series line.

In most instances, individual bulbs of higher voltage than has been conventional in connection with Christmas tree lighting are now being used such as bulbs on a 110 volt circuit. When it is found desirable because of the density of the branching of the Christmas tree adjacent its lower area to provide a branch distribution point, then a connector unit 21 such as is shown in the lower part of Figure 1 may be used. The unit 21 consists of a supply line 20 plugged into the adjacent socket 1 and an outlet member 21' to which bulbs may be permanently connected thereto by means of the lines 22, 23, and may also have individual plug-in connections such as is shown in the line 24 connected by means of the plug 25 with outlet member 21'.

The construction of the several units of the illumination system is shown in Figs. 2 to 9 of the drawing, Figs. 2 to 5 relating to the multiple plug socket and connections, Fig. 7 to the prong connection and clip, and Figs. 8 and 9 to the branch connector unit. As has been indicated, the conductor cable 1a preferably runs in unbroken continuity throughout the multiple plug sockets 1, the individual wires 2, 3, being stripped of insulation within each socket area. As is more clearly shown in Figs. 2 and 5, each multiple plug socket is formed of a body member 31 and a companion body member 32 in the form of elongated blocks of insulating material and their adjacent faces are formed with longitudinal grooves 33, 34, in parallel spaced relation extending over almost

the full length of the block, said grooves connecting at each end with the terminal recesses 35, 36, within which the main line cable 1a is received through the openings 37, 38, respectively, centrally of the ends of the combined body members. As will be observed the body members 31, 32, are similar in shape and construction for economical reasons and to facilitate assembly thereof.

The body members 31 and 32 are held in permanent contact with each other by suitable means, such as rivets 39, 40, or similar fastening devices. The grooves and recesses 33, 34 are formed in each of the adjacent faces of the members 31, 32, so that the wires 2, 3, will be firmly engaged therein and so that the main line cable 1a will have its insulated portion adjacent the multiple plug socket at each end housed within the respective terminal recess of the multiple plug socket which receives the stripped wires in the body portion of the socket after the insulation of the main conductor cable has been stripped therefrom.

Adjacent each of the longitudinal grooves or channels 33, 34, each of the members 31 and 32 of each of the multiple plug sockets 1 are formed with a series of pairs of plug contact receiving recesses 41. Each recess 41 is of somewhat larger diameter than the diameter of the contact prong it is to receive. The pairs of recesses 41 in one member are staggered in relation to those of its companion member, as shown in Fig. 2. Each of the larger recesses is continued into the intermediate area of the companion member in the form of a narrower recess 43 into which the outer end of the adjacent contact prong snugly extends after it has made contact with one of the stripped conductor wires 2, 3, positioned in the channels of the members 31, 32.

As will be observed in Fig. 5, the axes of the openings 41, 43, at the outer side of each wire 2, 3, are so related thereto as to insure a frictional engagement under pressure of the plug prong with the wire, to insure a positive electrical contact between these parts; also, that by providing for the support of each prong in both members 31, 32, at the inner and outer sides of the adjacent wire, danger of the electrical connection referred to being affected by lateral stresses on the outer end of the plug is reduced to a minimum.

The plugs 16 and sockets 18 of the individual lines 15 are preferably each of the solderless type. The plugs 16 must have contact prongs which snugly engage within the narrow recesses 43 after they contact the stripped conductor wires, as stated. Such prongs are preferably formed of cylindrical contact elements 45 (see Fig. 6) having fixed collars or circular enlargements 46 in spaced relation to one end and adapted to be received in suitable recesses in the plug body presently to be described. The end 47 of the contact prong adjacent the collar 46 is open so as to receive a stripped conductor wire 48 of the line 15, and have crimped engagement therewith by suitably clamping the wall of the tubular member upon the wire. The opposite end 49 of the prong is rounded so as to co-operate with the recesses in the members 31 and 32.

The prongs 45, after engagement with the respective wires of the adjacent line 15 are received in parallel recesses 51 in the complementary halves of the body of the plug 16. The recesses are especially shaped to receive the enlargements 46 which serve to hold the prongs firmly in position as they project beneath the base of the plug.

Thus each plug 16 is a solderless unit secured to one end of the line 15 and at the other end of said line a solderless socket 18 is provided within which is engaged a miniature lamp bulb 17.

The branch connector unit 21 is illustrated in Figs. 8 and 9, and permits the current to be distributed from points spaced away from the main line 1a along the trunk of the tree, thus reducing the length of the individual lines which may be required within the lower more heavily branched area of the tree. As stated, each unit 21 may also have one or more permanently attached branch lines or extensions 22, 23, as shown in Fig. 1.

The branch connector unit 21 is formed of insulating material and may receive current through the line 20 connected with one of the multiple plug sockets and received at its free end within an annular recess 52 provided between the unit halves which are firmly held together by means of a central rivet 52', which also passes through a central clamping block 53, having recesses adjacent the rivet shank into which shallow bosses 54, 55, disposed centrally of the enlargements 56, 57, of the inner walls of the unit project. The enlargements are each provided with small recesses adjacent the conductor line 20 to receive the inturned ends of the stripped wires 58, 59, on the terminating ends of the wires forming the line 20, these ends serving to provide firmly engaged solderless connections with the respective current distributing disks 61, 62. The disks 61, 62, as shown in Fig. 9 are of annular shape and are engaged over the respective shallow bosses 54, 55, which center them within the unit and anchor them securely to provide for frictional contact with the prongs of an individual line plug 15a. To provide for easy contact with the disks 61, 62, the margins of the disks have portions 63 which are flared toward the adjacent walls of the unit providing a contact rib 64 on the inward marginal areas against which the prongs of the plug 15a engage to complete the circuit.

As has been indicated, permanent lines 22, may be connected with the unit or a large number of individual plug connections 15a may be provided for in the manner shown in Fig. 8. When the permanent lines are attached to the respective disks the manner of forming the contact will be substantially identical with the connection of the inturned ends of the stripped wires 58, 59, of the conductor line 20.

The effect of the illumination system on the tree decorations is of outstanding character, as the substantially complete concealment of the conductor lines prevents any diversion of an observer's attention away from the purely artistic features of the assembled elements as a unitary design.

As stated, the entire system may be formed without the use of solder or the like.

Fig. 10 shows a connector unit 21a somewhat similar in construction to that shown in Figs. 8 and 9.

The unit 21a consists of two side walls 66, 66a, having axially disposed hollow bosses 67 and annular side walls 67a surrounding the bosses and arranged to form within the unit an annular recess 52a into which the prongs of a plug 15a and conductors 2, 3, extend. Annular disks 61a, 62a, formed of electric conducting material and surrounding the bosses 67 are secured to the inner faces of the walls 66, 66a, respectively, by a sleeve 68 surrounding the bosses 67 and formed of suitable insulating material, such as fiber. The disks

66, 66a, are secured together by a rivet 69. The sleeve 68 is cut to a length so as to engage the disks 61a, 62a, under pressure when the walls are secured together by the rivet 69. By preference, a clip 21x is attached exteriorly to one of the walls 66, 66a, by the rivet 69. The clip 21x is formed of resilient metal for engagement with a part of the display to support the unit thereon.

Figs. 11 and 12 illustrate a modified form of distributing device. In this embodiment of the invention the inner wall 31x of each body member 31, 32 (one of said members only being shown in Fig. 12), is extended at its opposite ends into the terminal recesses 35, 36, and enlarged to form heads 31x' having a transverse diameter greater than that of the openings through which the conductors 2, 3, pass; whereas the side walls of the adjacent recesses extend inwardly substantially parallel to the inner or reduced portions of the heads 31x'. When the body members 31, 32, are assembled, each head 31x' in one member is related to one of the heads in the other member and the sides thereof form with the side walls of the adjacent recesses 35-35 or 36-36 seats 31a of substantially arcuate shape for the lead-in portions of the conductors 2, 3, so that the latter are held against endwise movement; by preference the free end of each head 31x' is disposed in plane transverse to the axis of the wall 30 31x and disposed at substantially right angles to the sides of the head, so that those portions of the seats 31a defined by the free ends of the adjacent related heads provide angular sections in the conductors as shown at 2a, 3a, to interlock the conductors 2, 3, to the walls of the body members 31, 32, and hence prevent endwise movement of the conductors relative to the body members 31, 32. It will thus be observed that each distributing device 1 constitutes a unitary assembly and when the body members 31, 32, of each device are connected together, no additional electric connections are required. In fabrication any number of distributing devices 1 may be connected in spaced relation in a cable 1a; where too many devices are provided, the user may cut off the one most remote from the terminal plug 4 or as many additional devices 1 as desired without affecting the remaining devices.

In this form of construction, the outer end portion of each recess 41 is enlarged, as shown at 41a. The enlarged portion 41a is formed for the purpose of accommodating a sleeve 65 formed of suitable insulating material and mounted on each prong 45, as shown in Figs. 11 and 13. It will be observed that the sleeves 65 on the prongs 45 are disposed intermediate the ends thereof and when the latter are inserted in a pair of recesses 41 they extend outwardly beyond the outer face or surface of the device 1 and thus tend to eliminate short circuiting.

This application is a continuation in part of my co-pending application Ser. No. 667,947, filed May 7, 1946, now Letters Patent No. 2,558,029, dated June 26, 1951.

To those skilled in the art to which my invention relates many changes in construction and widely differing embodiments and applications thereof will be apparent without departing from the scope of the invention. The descriptions and disclosures herein are merely illustrative and not in any sense intended to be limiting.

What I claim is:

1. In a multiple plug socket adapted to enclose the continuous current conducting wires in and intermediate the ends of an insulated cable,

the combination of a pair of elongated members of similar shape and size and formed of insulating material, means for securing said members together, the inner walls of said members at opposite ends thereof being formed with related recesses forming inlet openings for lead-in wires, the inner wall of one of said members being formed with spaced parallel grooves extending longitudinally thereof connected with said openings, the wires of the cable co-extensive with said grooves being stripped of the insulation and seated in said grooves, respectively, each of said members being formed with a plurality of pairs of transversely extending through openings and the inner wall of the other member being formed with a plurality of pairs of recesses, each aligned with one of the pairs of through openings, the through openings of each pair thereof intersecting the conductor grooves, whereby the prongs of a plug when inserted in a selected pair of through openings contact the conductors, respectively, the through openings in one member and aligned recesses being staggered relative to the through openings and aligned recesses in the other member.

2. In a device for distributing electric current to a plurality of circuits, the combination of a pair of elongated members formed of insulating material, means for securing said members together, the inner walls of said members at each end thereof being formed with related recesses forming inlet openings for lead-in wires and the inner wall of one of said members being formed with spaced parallel grooves connected with said openings and extending longitudinally of said member, and conductors mounted in and co-extensive in length to said grooves and electrically connected to said lead-in wires, respectively, the side wall of one of said members being formed with a plurality of pairs of transversely extending through openings and the inner wall of the other member being formed with a plurality of pairs of transversely extending recesses, each aligned with one of said through openings, the through openings of each pair thereof intersecting the conductor grooves, whereby the prongs of a plug when inserted in a selected pair of through openings contact the conductors, respectively, said inlet openings within said members being enlarged and the wall between said grooves being extended at its opposite ends into said openings and terminating in heads to form substantially arcuate seats for those portions of the cable extending into said openings, the en-

gagement of the cable with the walls of the seats serving to prevent endwise movement of the cable and conductor wires relative to said members.

- 5 3. In a device for distributing electric current to a plurality of circuits, the combination of a pair of elongated members formed of insulating material, means for securing said members together, the inner walls of said members at each end thereof being formed with related recesses forming inlet openings for lead-in wires and the inner wall of one of said members being formed with spaced parallel grooves connected with said openings and extending longitudinally of said member, and conductors mounted in and co-extensive in length to said grooves and electrically connected to said lead-in wires, respectively, the side wall of one of said members being formed with a plurality of pairs of transversely extending through openings and the inner wall of the other member being formed with a plurality of pairs of recesses, each aligned with one of the pairs of through openings, the through openings of each pair thereof intersecting the conductor grooves, whereby the prongs of a plug when inserted in a selected pair of through openings contact the conductors, respectively, the through openings in one member and aligned recesses being staggered relative to the through openings and aligned recesses in the other member.
